HAND SWEEPER

Saul Langner, 12 W. 27th St., New York, N.Y.

Filed Apr. 11, 1966, Ser. No. 1,853

Term of patent 14 years

(Cl. D9—2)

FIG. 2 is a top plan view thereof.

FIG. 3 is a side elevational view thereof.

FIG. 4 is an end elevational view thereof, and

FIG. 5 is a bottom plan view thereof.

I claim:

The ornamental design for a hand sweeper, substantially as shown.
